DUMP HOIST

Charles Martelock, Berkeley, Calif.

Application April 23, 1935, Serial No. 17,869

6 Claims. (Cl. 214—120)

My invention relates to improvements in dump hoists, and it consists of the combinations, constructions and arrangements hereinafter described and claimed.

5 An object of my invention is to provide a dump hoist which is primarily designed for mine shafts, and which can be operated by one man who is stationed within the mine. The device makes use of a safety feature in which a holding lever prevents the dumping of the bucket until the bucket reaches the proper position. This holding lever does away with the necessity of providing a guide rail for the bucket where the bucket is of the counter-balanced type. A 10 locking lever cooperates with the bucket-holding lever and prevents the accidental movement of the holding lever until the bucket reaches dumping position.

A further feature lies in the provision of a 20 bucket carrier movable along the guide rails, this carrier being relatively long, and being movable into positions to extend a predetermined distance above the guide rails, or below the guide rails when the bucket is moved into its two extreme 25 positions. This arrangement permits the guide rails to be shorter in length than would be otherwise necessary.

The device makes use of a swingable chute, and further makes use of a roller designed to engage 30 with the bucket during dumping movement. The counter-balance is also connected with the bucket carrier, and means is provided on the counter-balance for lengthening the cables connecting it with the bucket carrier. In this simple way 35 the distance through which the bucket carrier moves can be changed at will.

A modified form of the invention is shown and 40 illustrates the means for causing the counter-balance to move past the bucket carrier when the entire device is inclined from the vertical. This form of the device is adapted for mine shafts extending at an angle into the earth.

Other objects and advantages will appear in 45 the following specification, and the novel features of the device will be particularly pointed out in the appended claims.

My invention is illustrated in the accompanying drawings forming a part of this application, 50 in which

Figure 1 is a vertical transverse section through the device, portions being shown in elevation;

Figure 2 is a rear elevation of Figure 1;

Figure 3 is a view similar to Figure 1, but showing the parts in a different position;

Figure 4 is also a view similar to Figure 1, but showing the bucket in dumping position;

Figure 5 is a rear elevation of the counter-balance;

Figure 6 is a section along the line 6—6 of 5 Figure 5;

Figure 7 is a side elevation of a modified form of the invention shown adapted for inclined mine shafts;

Figure 8 is a rear elevation of a portion of 10 Figure 7; and

Figure 9 is a section along the line 9—9 of Figure 8.

In carrying out my invention I provide a frame indicated generally at 1. This frame carries two 15 guide rails 2 and 3, see Figure 2. These rails extend a considerable distance above the ground level 4, and also extend any predetermined distance into a mine shaft 5. Although the device is adapted for use in mines, it is obvious that 20 it can be used for any other purpose for which dump buckets are adapted.

I provide a bucket carrier indicated generally at 6 and it will be noted that this carrier comprises two elongated shoes 7—7 disposed on each 25 of the guides 2 and 3. Figure 1 shows how the shoes 7—7 slidably contact with opposite sides of the guide 2. The shoes are connected together by cross pieces 8, and the shoes on opposite guides are connected together by cross pieces 30 9. It will be seen from this that the bucket carrier 6 can freely slide along the guides 2 and 3, and the length of the shoes 7 is such as to permit the top portion of the carrier to be moved above the top of the guides 2 and 3 when the carrier is 35 in its extreme uppermost position, and to permit the bottoms of the shoes 7—7 to extend below the bottoms of the guides 2 and 3 when the carrier is in its extreme lowermost position. This permits the guide rails 2 and 3 to be made shorter 40 than it would otherwise be necessary. Furthermore the guide rails 2 and 3 can terminate above the bottom of the mine shaft 5, and this will give more freedom to the operator for digging purposes.

The device is designed primarily for operation by one man, and the operator can actuate the device from a position within the mine shaft 5. To this end I provide a counterbalance weight indicated generally at 10, and this weight is connected to the bucket carrier 6 by cables 11 and 12, 50 see Figure 2. Another cable 13 is connected to the weight 10, and to the bottom of the bucket carrier 6.

The weight is shown in detail in Figures 5 and 55

6. Figure 5 shows the weight 10 as comprising a casing in which a spool 14 is rotatably mounted. The spool is secured to a shaft 15 and has the cables 11 and 12 wrapped therearound. Figure 5 shows the cables 11 and 12 passed over idlers 16 and 17.

10 A hand crank 18 is pivoted to the shaft 15 at 19 and it may be swung from the full line position shown in Figure 6 to the dotted line position, and 10 then rotated for either winding the cables 11 and 12 onto the spool 14, or for unwinding the cables therefrom. In this simple way the effective length of the cables 11 and 12 is varied and the distance through which the bucket carrier 6 can 15 move is also varied.

15 In order to lock the spool 14 against accidental rotation I provide a ratchet 20 which is rigidly secured to the shaft 15 and I also mount a pawl 21 on the casing 10, this pawl engaging with the 20 ratchet to prevent the unwinding of the spool or reel 14. As a further means of locking the device I provide the casing 10 with an opening 22 for receiving the end of the crank handle 18.

25 When the effective lengths of the cables 11 and 12 are altered it is necessary to also alter the effective length of the cable 13. In Figures 5 and 6 I show the cable 13 as being secured to the casing 10 at 23. The cable is then wrapped around a support 24 through a number of turns 30 as shown at 25 and then the free end of the cable is passed through a hook 26. If it is desired to shorten the overall length of the cable 13, it is merely necessary to wrap a few more turns of the cable around the support 24, and 35 then to pass the free end through the hook 26. This will prevent the turns of the cable 25 from unwinding. On the other hand, if it is desired to lengthen the overall length of the cable 13, the portion of the cable passing through the hook 40 26 can be temporarily freed, and then a number of turns of the cable unwound from the support 24, whereupon the free end of the cable can again be passed through the hook 26. In this 45 simple way the effective length of the cable 13 is changed.

Another important feature of the invention is its safety device for holding the bucket against 50 accidental dumping. In Figure 1 I show a bucket 27 mounted upon a platform 28 which, in turn, is pivoted 55 carried by the bucket carrier 6 at 29. The pivot point is slightly off center so that the tendency of the bucket 27 will be to swing in a clockwise direction about the pivot 29. Usually where such a bucket is provided a guide rail is 55 also used against which the bucket slides as it is moved vertically. I do away with the necessity of such a guide rail, and instead I provide a holding lever 30 which is pivoted to the carrier 6 at 31. This lever is so weighted as to engage 60 with the front edge of the bucket 27, and to hold it against dumping.

In order to prevent the lever 30 from accidentally releasing the bucket 27 I provide a locking lever 32 which is pivoted to the carrier 6 at 33. 65 This lever 32 has a portion 34 that is designed to pass between the projections 35 carried by the lever 30, and to hold the lever 30 against accidental swinging. When the bucket is moving along the guides 2 and 3 the levers 30 and 32 will 70 assume the positions shown in Figure 1. It will be seen that the bucket 27 is held against accidental dumping, and that a guide rail for the bucket is not necessary.

75 In Figures 3 and 4 I show in detail how the levers 30 and 32 are actuated for freeing the

bucket 27 when the bucket reaches dumping position. A cam rail 36 parallels the guide rail 2 for a predetermined distance, and is disposed in the path of the levers 30 and 32. The lower end of the cam rail 36 has a beveled portion 37 for engaging with the portions 38 and 39 of the levers 30 and 32 respectively. Figure 3 illustrates how the locking lever 32 is swung into a position by the cam rail 36 to free the portion 34 from the projections 35. The holding lever 30 is now 10 free to swing but its weight will still hold it in the position shown in Figure 3. Before the locking lever 32 contacts with the cam rail 36, the forward edge 40 of the bucket 27 will have passed 15 behind a guide plate 41, and therefore should the holding lever 30 accidentally free the bucket 15 the guide plate 41 will prevent its dumping.

As the bucket carrier 6 moves upwardly the portion 38 of the lever 30 will contact with the cam rail 36, and this will swing the holding lever 20 30 into the position shown in Figure 4. This swinging movement is timed to take place when the forward edge 40 of the bucket reaches the top of the member 41. The portion 38 strikes the rear of the bucket during the swinging of 25 the lever 30, and starts the bucket swinging about its pivot 29. A roller 42 is mounted at the top of the member 41 in order to aid in the dumping of the bucket.

The bucket in dumping leaves its support 9' 30 and should the bucket be carried above the roller 42, it will again contact with the under side of the member 9' and prevent further swinging movement of the bucket. A skid rail 43 is mounted on the front of the bucket and rides 35 over the roller 42 during the dumping movement.

When the bucket is returned to the bottom of the mine shaft it will swing back into normal 40 position due to the roller 42. The holding lever 30 will engage with the bucket as soon as this lever clears the cam rail 36. Also the locking lever 32 will engage with the holding lever 30 as soon as the lever 32 clears the cam rail 36. The bucket is now held against dumping and can 45 be lowered to the bottom of the mine shaft 5 for another load.

The operator, in raising the bucket, merely 50 pulls upon the cable 13 so as to lower the counter-balance 10. The counter-balance 10 practically 55 balances the weight of the bucket 27, and therefore one man can raise the filled bucket. After 60 dumping has taken place the cable 13 can be again pulled upon by the operator so that the bucket carrier 6 will be lowered.

In Figure 1 I show a swingable chute. This chute comprises arms 44 pivoted to the guide rails 2 and 3 at 45. A chute 46 is carried by the arms and has a hinged portion 47 which contacts with the roller 42 regardless of the angle 65 of the chute. A cable 48 may be secured to the rear ends of the arms 44 and the driver of the truck 49 can pull upon this cable for swinging the chute into a position to dump the material 70 into the truck.

If desired the device may be operated by power 75 instead of by hand. This shaft carries pulleys 51 over which the cables 11 and 12 are passed. It is obvious that a rotation of the shaft 50 will move the cables, and this in turn will 80 actuate the device. If power is used the counter-balance 10 can be made heavier than the empty bucket 27, and then when a load is placed in the bucket the loaded bucket will be but slightly 85 heavier than the counter-balance. In this way 75

a small amount of power will be needed for moving the bucket when loaded or unloaded.

In Figures 7 to 9 inclusive I show a slightly modified form of the invention. In this form the guide rails 75 are inclined from the vertical, and Figure 7 shows these rails entering an inclined mine shaft 76. The rails may be supported in a frame indicated generally at 77, and I have indicated a portion of this frame resting on the ground line 78.

A bucket carrier 79 slides along the rails 75, and pivotally carries a bucket 80. A counter-balance 81 is connected to the bucket carrier 79 by cables 82. The counter-balance has runners 83 that ride on the rails 75. These runners are supported by shoes 84 which have their ends turned upwardly as shown in Figure 7. These shoes slidably engage with arcuate guide rails 85 carried by the bucket carrier 79 when the counter-balance passes the bucket carrier. When the shoes 84 are on the rails 85 the runners 83 prevent lateral movement between the counter-balance 81 and the bucket carrier 79. The ends of the arcuate guides 85 extend below the upper edges of the rails 75 and cam the counter-weight 81 off from the rails 75 during the time the bucket carrier 79 passes the counter-balance. The upper edges 86 of the bucket carrier 79 are provided with inclined ends 87 which aid in lifting the counter-balance 81 off from the guides 75. It will be seen from this construction that both the bucket carrier 79 and the counter-weight 81 have freedom of movement throughout the entire length of the rails 75.

In order to permit the bucket carrier 79 to have a portion project beyond the tops of the rails 75 I dispense with the shaft 50 and instead mount pulleys 88 corresponding to the pulleys 51 on stub shafts 89.

The bucket 80, see Figure 9, is held in the position shown by a holding lever 90 and a locking lever 91 similar to the levers 30 and 32, with the exception that the lever 90 and 91 are shaped to accommodate the bucket in an inclined position. The two levers 90 and 91 act in identically the same way as levers 30 and 32 when the levers 90 and 91 pass beneath a cam guide 92 which is similar to the cam or rail 36.

All other parts of the modified form of the invention are identical to those described in the form shown in Figures 1 to 6 inclusive, and therefore no further description need be given.

In the operation of the device, whether the rails are vertically disposed, or are inclined, the bucket carrier and the counter-balance will have freedom of movement throughout the entire length of the guide rails. The modified form of the device has only those additional parts added thereto which will adapt it to enter an inclined mine shaft.

While I have shown only the preferred forms of my invention, it should be understood that various changes or modifications may be made within the scope of the appended claims with-

out departing from the spirit of the invention.

I claim:

1. A dump hoist comprising a frame, a bucket carrier slidably carried by the frame, a bucket pivotally supported by the carrier and being overbalanced to swing into dumping position, a holding lever mounted on the carrier and engaging with the bucket for preventing its dumping, a locking lever engaging with the holding lever for positively locking it against accidental swinging, and a cam placed in the path of said levers for first freeing the locking lever from the holding lever and then the holding lever from the bucket for permitting the bucket to dump. 5

2. A dump hoist comprising a frame, a bucket carrier slidably carried by the frame, a bucket pivotally supported by the carrier and being overbalanced to swing into dumping position, a holding lever mounted on the carrier and engaging with the bucket for preventing its dumping, a 10 locking lever engaging with the holding lever for positively locking it against accidental swinging, and a cam placed in the path of said levers for first freeing the locking lever from the holding lever and then the holding lever from the bucket for permitting the bucket to dump, a bucket-retaining member positioned to receive the bucket when the two levers are released, and a roller mounted on the top of the member for guiding the bucket into dumping position. 15

3. A dump hoist comprising guide rails, a bucket carrier slidably along the rails, a counter-balance, cables connecting the carrier with the counter-balance, and a reel carried by the counter-balance and having the ends of the cable 20 wrapped therearound, whereby the cables can be unwound from or wound around the reel for changing the effective lengths of the cables, an operating cable connected between the counter-balance and the carrier, and means on the counter-balance for supporting any unused portion of the last named cable, whereby its effective length can be altered at will. 25

4. A dump hoist comprising inclined guide rails, a bucket carrier slidable therealong, a 25 counter-balance also slidable on the rails and being operatively connected to the carrier, and guide rails on the carrier for supporting the counter-balance when the counter-balance passes the carrier. 30

5. In a dump hoist, a bucket carrier, a bucket pivotally carried thereby, a holding lever engaging with the bucket, a locking lever for positively locking the holding lever, and means for successively moving first the locking lever and 35 then the holding lever for freeing the bucket.

6. In a dump hoist, an inclined bucket carrier, inclined rails slidably supporting the carrier, arcuate rails attached to the carrier, and a counter-weight connected to the carrier, said 40 counter-weight being slidable over the inclined rails and the arcuate rails.

CHARLES MARTELOCK.
